ALFRED HOPKINSON, OF HYDE, ENGLAND.

BRAIDING MACHINE.

Application filed March 16, 1927, Serial No. 175,885, and in Great Britain April 28, 1926.

This invention relates to the tension and thread or yarn releasing device for braiding machine to maintain the thread taut and compensate for slackness caused by the varying 5 length of the thread as it passes from one bobbin over and under another bobbin.

The thread or yarn holder is ordinarily constructed with a flange notched or indented against which a detent lever or pawl engages 10 or with a flange against which a brake contacts to lock or hold the bobbin against rotation until released and a pivoted spring controlled tension lever with guides at one or both ends over which the thread passes, which 15 as the tension thereon increases is moved to withdraw the pawl or brake and release the bobbin.

According to the invention the device comprises a pivoted lever carrying a brake block 20 to engage the flange of the thread holder, a spring controlled oscillating two member tension lever, one member of which is longer than the other, the long member being provided with (or connected with) a thread eye 25 or guide moving with it and its short member with or without a thread eye or guide adjacent to and acting upon the brake lever, a fixed guide or guides around or through which the thread passes so disposed in relation to the tension lever that the movement of 30 the long member of the lever in one direction will decrease the path of the thread and in the other direction will increase the path of the thread, the short member of the lever engaging the brake lever to release or withdraw the 35 brake from the yarn holder when the tension reaches its limit to permit the drawing off from the bobbin a further supply of thread.

The invention will be fully described with 40 reference to the accompanying drawings in which the invention is shown detached from the braiding machine.

Fig. 1 is a front elevation of one form of the invention.

Fig. 2 is a side elevation.

Fig. 3 is a plan.

Fig. 4 is a front elevation of another form of the invention.

Fig. 5 is a side elevation of same.

Fig. 6 is a plan.

Fig. 7 is a perspective view showing another form.

The rotary thread holder A or A¹ is of known construction mounted on a plate C or C² to rotate as the thread is drawn off therefrom with a flange a or a¹ and central spindle a¹ or

a² to hold the thread supply, the flange being acted upon by a brake B or B¹, to prevent rotation while a supply of thread is not required to be drawn off the bobbin. 60

The brake B or B¹ is carried by a brake lever b, b¹ or b² pivoted and fulcrumed at one end upon the plate C or C² and of such a length that the power required to move it against the pull of a strong spring G¹ or G² is 65 very slight. The brake lever b or b¹ is horizontal and the brake block B or B¹ thereon engages and is pressed against the flange a or a¹ of the bobbin carrier A or A¹ by the spring G¹ or G². The free end of the lever b or b¹ 70 extends to one side of the thread holder A or A¹ to be engaged by the short member of a tension lever also carried upon the plate C or C² operated by the tension of or pull of the thread. This construction effects a smooth 75 and practically constant tension on the thread as the release takes place with a minimum amount of force or pressure on the long arm of the tension lever and obviates any jar or unevenness in the release of the thread from 80 the bobbin.

In the form shown in Figs. 1 to 3 on the plate or bracket C upon which the thread holder A is mounted, a spring controlled two member lever D capable of being oscillated or rocked to one side or the other is pivoted or fulcrumed upon a pivot d² much nearer to one end than the other so that one arm or member d³ is much longer than the other member d⁴, the shorter arm or member d⁴ being adjacent 90 to the free end of the brake lever b. It is formed with a thread eye or thread guide at both ends preferably guide roller d and d¹. An adjustable spring G is fitted to hold the lever D in working position against the pull 95 of the thread x passing over the guide rollers d, d¹, or through a guide eye at the end of the long member d³. Two thread eyes or thread guides c, c¹ on posts C, C², respectively are 100 fixed to the plate C in any position a suitable distance apart to direct the yarn x off the bobbin E and towards the braiding eye. The thread x is passed around a vertical guide post H through the two fixed guide eyes c, c¹ and around the guide rollers d, d¹ of the oscillating lever D and as the pull on the thread increases the long member d³ of the lever D is 105 rocked in a forward direction decreasing the path of the thread between the two guide eyes, easing the tension and finally pulling the lever so far over that the short member d⁴ engages the end of the brake lever b with.

drawing the brake B and permitting a further supply of thread to unwind from the bobbin. As the tension or pull on the thread is thereby reduced the lever D is rocked in 5 the reverse direction, the path of the thread between the guide eyes c, c¹ increased and any slack in the thread taken up thereby maintaining it at an even tension. The same movement takes place when the path of the 10 thread is increased between the guide eye c¹ and the braiding centre consequent upon passing over and under the bobbin of the inner set the tension on the thread being kept practically constant.

15 In addition to the guide rollers d, d¹ the thread may also pass round a light spring finger K affixed to the stem or post C¹ of the guide eye c which while normal tension is maintained will be drawn away from the 20 post (see Fig. 2) but should the tension cease through too much thread being unwound from the bobbin the finger K will spring back against the post C¹ and trap and hold the thread until normal tension is restored. A 25 stop rod M is suspended from the yarn x which when the yarn breaks or becomes too slack falls through the tube m in which it is suspended and engages a stop motion (not shown).

30 In the form shown in Fig. 7 a spring controlled two member lever N¹ having one arm longer than the other and capable of being oscillated or rocked is pivoted upon a bracket on a plate C² with its short member n⁵ adjacent to the free end of a brake lever b² which is similar to that shown in plan Fig. 6. The lever N¹ is formed with a thread guide or eye n³ at the end of the long arm n⁶ and a thread guide or eye c³ on a vertical guide 35 post is fitted to the plate C² at a suitable distance from the eye n³ to direct the thread x toward the braiding eye. The lever N¹ is connected by a link n⁴ to a stop rod M² and is drawn down by a spring as in Figs. 4 and 40 5. The yarn x¹ is passed around a vertical guide post as in Fig. 4 through the eye n³ in the oscillating lever N¹ and through the fixed guide eye. As the pull of the thread increases the lever N¹ is rocked upwards decreasing the path of the thread easing the tension and finally pulling the lever so far that the short arm or member n⁵ engages the end b² of the brake lever withdrawing the brake 45 and permitting a further supply of thread to unwind from the bobbin. As the pull of the thread is thereby reduced the lever N¹ is rocked in the reverse direction, the path of the thread is increased and any slack taken up maintaining the tension even.

50 In the form shown in Figs. 4 to 6 on the plate or bracket C² upon which a thread holder A with a flange a² and a central spindle a³ is mounted, a spring controlled two member lever N one arm or member longer 55 than the other, capable of being oscillated

or rocked is pivoted the short arm or member adjacent to the free end of the brake lever b¹. The long arm or member n¹ of the lever N is connected by a link n to a movable rod M¹ provided with a thread guide or eye m¹. Thread x² passes around a vertical post H¹ to a thread guide or eye c² on a vertical guide post fitted to the plate C² at a suitable distance from the eye m¹ to direct the thread x² toward the braiding eye. The brake lever b¹ carrying the brake block B¹ is pivoted to oscillate below the bobbin carrier A¹, the brake being applied to the flange a³ of the bobbin carrier A¹ by a spring G². The lever N is drawn down and tension applied to the 80 thread x² as it passes through the guide eye m¹ by a spring G³. The rod M¹ also serves as a stop rod to stop the machine when the thread x² breaks or becomes too slack. As the tension on the thread increases the rod 85 M¹ is raised and the lever N rocked until the end n² engages the free end of the brake lever b¹ and relieves the pressure of the brake block B¹ upon the flange a³ of the bobbin carrier, and permits a further supply of thread to be 90 unwound, on the tension of the thread being thus reduced the lever N rocks in the reverse direction again applying the brake to maintain a constant tension.

In normal position of the tension lever 95 the brake engages the yarn holder flange to retain it from rotation but when the tension lever is rocked to any great extent it engages the brake lever and releases the bobbin holder.

The invention may be applied to either 100 the outer or inner bobbins of the braiding machine.

What I claim as my invention and desire to protect by Letters Patent is:—

1. A tension device for braiding machines 105 comprising a flanged thread holder, a pivoted lever carrying a brake block to engage the flange of the thread holder, a spring controlled rocking lever having one member much longer than the other, the long member being provided with a thread guide or eye 110 moving with it and the short member adjacent to and acting upon the brake lever, a fixed guide or guides around or through which the thread passes so disposed in relation to the rocking lever that the movement of the long member of the lever in one direction will decrease the path of the thread, and in the other will increase the path of the thread, the short arm or member of the 115 lever releasing or withdrawing the brake from the yarn holder when the tension reaches its limit, to permit the drawing off from the bobbin a further supply of thread.

2. A tension device for braiding machines 125 comprising the combination of a brake lever and brake, a thread holder, a flange thereon upon which the brake lever and brake act, two thread guides or eyes relatively disposed at a constant distance apart, a spring controlled 130

rocking lever divided into two members one longer than the other and provided with a thread guide at each end around or through which the thread from the bobbin is passed, 5 the rocking lever being so disposed in relation to the fixed thread guides or eyes that the movement in one direction will shorten the path of the thread, increase the tension

and finally release the brake, and movement in the other direction will lengthen the path 10 of the thread and take up the slack between the fixed thread eyes or guides substantially as described.

In testimony whereof I have hereunto set my hand.

ALFRED HOPKINSON.
